US00D909058S

(12) **United States Design Patent** (10) **Patent No.:** **US D909,058 S**
(45) **Date of Patent:** **** Feb. 2, 2021**

(54) **CARD WALLET**

D741,598 S * 10/2015 Calero D3/303
D802,921 S * 11/2017 Barnet D3/247

(71) Applicant: **SUMSAARA LLC**, Dublin, CA (US)

* cited by examiner

(72) Inventor: **Jannat Saxena**, Dublin, CA (US)

Primary Examiner — Holly H Bayham

(73) Assignee: **SUMSAARA LLC**, Dublin, CA (US)

(74) *Attorney, Agent, or Firm* — Loza & Loza, LLP;
Michael F. Fedrick

(**) Term: **15 Years**

CLAIM

(21) Appl. No.: **29/706,159**

The ornamental design for a card wallet, as shown and described.

(22) Filed: **Sep. 18, 2019**

DESCRIPTION

(51) **LOC (13) Cl.** **03-01**

FIG. 1 is a front perspective view of a card wallet, showing my new design;

(52) **U.S. Cl.**

FIG. 2 is a front elevational view thereof;

USPC **D3/247**

FIG. 3 is a left side elevational view thereof, the right side elevational view being a mirror image of the left side elevational view;

USPC D3/247, 249–253

FIG. 4 is a top plan view thereof;

CPC A45C 1/06; A45C 11/18; A45C 11/182;

FIG. 5 is a rear perspective view thereof;

A45C 13/30

FIG. 6 is a rear elevational view thereof; and,

See application file for complete search history.

FIG. 7 is a bottom plan view thereof.

(56) **References Cited**

The stippled shading in the views indicates a surface contrast in color and/or texture between visible interior and exterior surfaces of the card wallet. The oblong shapes having curved diagonal lines depict lines of stitching that do form a part of the claimed design.
